(57) **CLAIM**

The ornamental design for a wireless entrance communication device, as shown and described.

DESCRIPTION

FIG. 1 is a front perspective view of a preferred embodiment of the wireless entrance communication device according to the present design;

FIG. 2 is a front elevational view of the wireless entrance communication device of FIG. 1;

FIG. 3 is a rear elevational view of the wireless entrance communication device of FIG. 1;

FIG. 4 is a left-side elevational view of the wireless entrance communication device of FIG. 1, the right-side elevational view being a mirror image thereof;

FIG. 5 is a top plan view of the wireless entrance communication device of FIG. 1; and,

FIG. 6 is a bottom plan view of the wireless entrance communication device of FIG. 1.

The broken line showing of features and mounting elements is included for the purpose of illustrating portions of the wireless entrance communication device, and forms no part of the claimed design.
